UNITED STATES PATENT OFFICE.

ANDREW NILSON, OF CHICAGO, ILLINOIS, ASSIGNOR TO THE EUREKA SMOKELESS FURNACE COMPANY, OF CHICAGO, ILLINOIS, A CORPORATION OF ILLINOIS.

FURNACE.

1,287,081.

Specification of Letters Patent. Patented Dec. 10, 1918.

Application filed January 19, 1917. Serial No. 143,228.

To all whom it may concern:

Be it known that I, ANDREW NILSON, a citizen of the United States, residing at Chicago, in the county of Cook and State of Illinois, have invented a certain new and useful Improvement in Furnaces, of which the following is a full, clear, concise, and exact description, reference being had to the accompanying drawings, forming a part of this specification.

My invention relates to furnaces and more particularly to that style of furnaces in which a baffle wall or similar structure is used. My invention concerns itself more particularly with means for supporting such a baffle wall or similar structure. In providing supporting means of this nature it must be borne in mind that the supporting means is utilized at a zone of intense heat and that therefore the construction must be such as to withstand this heat in the continued operation of the furnace.

The supporting means which I have designed contemplate a tube or like structure having water therein for the purposes of cooling. This water is of course desirably the same water that is used for the furnace proper. When using the water from the furnace, this support is of course connected so that it communicates with the interior of the water chamber of the furnace.

In many trials it has been found that the mere connection of such a support between the water legs of the boiler does not accomplish the desired end, in that, this supporting structure happens to be at a portion of intense heat and the tendency of the water therein to flow in opposite directions fails to provide a fresh supply of cooling water.

The heating of this supporting structure or bridge therein then continues until the heat becomes too great for the said bridge to stand and it buckles under the weight of the baffle wall or other structure placed thereon.

My invention herein concerns itself with the arrangement of such a water cooled bridge so that proper circulation may be had, whereby the said bridge may maintain its condition even though it is continuously within the zone of probably the most intense heat, the construction of the bridge support being such that it can be readily mounted in place in boilers in operation, or may be readily taken out and replaced.

I will explain my invention more in detail by referring to the accompanying drawings illustrating the same, in which:

Figure 1 is a transverse sectional view of a furnace showing my improved bridge structure;

Fig. 2 is a sectional view on line 2—2 of Fig. 1;

Fig. 3 is a side view partly in section of the furnace shown in Fig. 1, and

Fig. 4 is a fragmentary perspective view illustrating a portion of the baffle wall structure.

Referring to the drawings, I show a furnace structure having the grate 10 above which there is what I might call the fuel chamber 11 and combustion chamber 12. The boiler 13 has the water legs 14, 14 as customary therein. The fuel 15 is shown as disposed upon the grate partially closing the space from the grate upwardly to a baffle wall structure 16. This baffle wall structure in the particular embodiment herein closes the space from the fuel upwardly through the boiler and consists substantially of masonry 17 and tile elements 18 and 19 respectively. The tile elements 18 and 19 are so arranged that they provide channels whereby the gases may flow from the fuel chamber through the baffle wall into the combustion chamber. The supporting means maintaining this baffle wall in position are the subject matter of my present invention. These supporting means include a tube 21 which tube directly supports this baffle wall structure, it being desirable in the particular embodiment herein to provide a groove 22 in the tile elements 18 to accommodate this tube 21. The tube 21 at its left hand extremity (Fig. 1) communicates directly with the interior of the left hand water leg 14. The tube, however, does not communicate with the right hand water leg 14 but extends therethrough and communicates with the lower portion of the right hand water leg 14 as shown at 23 through the interposition of the connecting tube 24. Of course, the tube 21 when it passes through the right hand water leg 14 is expanded so as to prevent leakage. In order to properly expand the supporting structure when it engages the walls of the water leg, I provide extension tubes 25 and 26 which project outwardly through the wall 27 of the furnace. Suitable caps 28 are

110

then provided to close up these tubes 25 and 26.

With the structure as thus outlined it will be readily apparent that the heating of the water in the tube 21 causes the results in a circulation as the cooler water is drawn from the lower portion of the right hand water leg 14 and this water may circulate upwardly into the left hand water leg 14 (Fig. 1). Of course it is not necessary, as will be obvious to those skilled in the art to use the specific portions of the water legs herein shown from which to draw the water in which to create circulation as any other suitable portions of the furnace proper where differences of temperature exist can be as readily chosen.

Having however thus described one form which my invention may take, what I claim 20 as new and desire to secure by Letters Patent is:

1. In a boiler having water legs, a tubular support for a baffle wall or similar structure, consisting of a tube connected to the inner wall of one of said water legs of the boiler and projecting through the other water leg, the interior of said tube at said connection with the inner wall aforesaid communicating therewith the interior of the boiler, and said tube at its projection through the said other water leg having a watertight connection with the two walls of said other water leg, a second tube secured to the outer wall of the second water leg, and a connecting tube between said second tube and the projecting portion of the first afore- 30 said tube.

2. In a boiler having water legs, a tubular support for a baffle wall or similar structure, consisting of a tube connected to the inner wall of one of said water legs of the

boiler and projecting through the other water leg, the interior of said tube at said connection with the inner wall aforesaid communicating therewith the interior of the boiler, and said tube at its projection through the said other water leg having a watertight connection with the two walls of said other water leg, a second tube secured to the outer wall of the second water leg, a connecting tube between said second tube and the projecting portion of the first aforesaid tube, and T connections interposed between said connecting tube and said other tubes. 45 50 55

3. In a boiler having water legs, a tubular support for a baffle wall or similar structure, consisting of a tube connected to the inner wall of one of said water legs of the boiler and projecting through the other water leg, the interior of said tube at said connection with the inner wall aforesaid communicating therewith the interior of the boiler, and said tube at its projection through the said other water leg having a watertight connection with the two walls of said other water leg, a second tube secured to the outer wall of the second water leg, a connecting tube between said second tube and the projecting portion of the first aforesaid tube, T-connections interposed between said connecting tube and said other tubes, and additional tubes projecting from 60 65 70 75 said T connections exteriorly of said boiler.

In witness whereof, I hereunto subscribe my name this 16th day of December, A. D., 1916.

ANDREW NILSON.
